UNITED STATES PATENT OFFICE.

WILLIAM LARKIN, OF TACOMA, WASHINGTON.

REFLECTOR.

1,333,551.

Specification of Letters Patent.

Patented Mar. 9, 1920.

Application filed May 4, 1918. Serial No. 232,542.

To all whom it may concern:

Be it known that I, WILLIAM LARKIN, a citizen of the United States, residing at Tacoma, in the county of Pierce and State of Washington, have invented new and useful Improvements in Reflectors, of which the following is a specification.

This invention is an improved reflector for use as a signaling device along highways 10 railroads, shore lines and in other places where lights may be directed upon the reflector from an exterior source such as by the headlights of automobiles or from the search lights of vessels or the like. My invention is also adapted for use in tail lights 15 on automobiles, wagons, bicycles and other vehicles and also in illuminated signs.

The object of the invention is to provide an improved reflector of this kind which utilizes 20 the light proceeding from an external source to produce a luminous signal and to thus mark a dangerous place on a road, a railway crossing, a wharf or the like and which may also be caused to produce a colored light, if this be desired.

The invention consists in the combination 30 of a reflector and a panel arranged for illumination by rays of light transmitted from the exterior through said panel and reflected by said reflector, as hereinafter described and claimed.

In the accompanying drawings:—

Figure 1 is a face view of a signaling reflector constructed and arranged in accordance with my invention.

Fig. 2 is a transverse sectional view of the same.

Referring first to the form of the invention shown in Figs. 1 and 2 the reflector 1 is 40 of truncated conical form and is provided with a centrally arranged oppositely inclined conical reflector 2 which extends into the space contained within the reflector 1. The annular reflecting surfaces 3 and 4 are preferably as shown wherein they are arranged 45 at right angles to each other, the base of the central reflector joining the truncated end of the outer reflector 1.

A transparent or translucent signaling 50 panel 5 extends across the base of the reflector 1 and comprises a colored central portion 6 and a clear surrounding or outer portion 7. The panel may be made of glass or of any other suitable material.

The reflector may be secured on a post or other supporting object and arranged at one

side of a roadway, at a dangerous point, or at a railway crossing, or at a wharf, or at any other desired place and is so held as to be illuminated by the rays of light from the 60 headlights of an approaching automobile, boat or vehicle. Such rays of light are reflected by the surfaces 3, 4 through the panel so that the panel is strongly illuminated and hence the said reflector makes its presence 65 known and operates as a signal, as will be understood. When the colored portion 6 of the panel is provided the reflector produces a colored light.

Light rays striking the clear annular zone 70 7 of the panel, pass freely through, strike the conical reflector 3, are reflected across to the reflector 4 and from thence to the inner surface of the colored center 6. Part of this light may pass through this colored center 75 and will be given the color thereof. Much of this light will, however, be reflected back upon the central reflecting cone 4, thence across to the outer conical reflector 3 and thence out through the panel 7 back to the 80 original exterior source of light.

In consequence of the action described, the central colored section will be seen, by the reflection of its inner surface, over the entire area of the surrounding annular zone 7. In 85 consequence, the entire area of the glass face 5 will appear illuminated and colored as is the center 6.

When constructed as described and with the diameter of the central panel 6 substantially equal to the diameter of reflector 4, the device, when seen from in line with the exterior source of illumination, will show 90 illuminated over its entire face and as having the color of the central panel 6.

If the signal be placed at a slightly different angle so that the rays of light are inclined to the common axis of the cones 3 and 4, this illumination would be directed, not directly back to the source of the light, but 100 somewhat to one side. It may, therefore, be used to give a warning down the opposite side of a sharp reverse turn or back along an angularly intersecting road.

The reflector may also be used as a tail 105 light for an automobile or other vehicle and will become illuminated and will serve efficiently as a signal when the automobile is approached from the rear by another having headlights, the rays of light from the headlights of the following automobile being utilized 110 to illuminate the reflector.

Having thus described my invention, I claim:—

1. In a signal the combination with a lens having a central colored section and a surrounding transparent section of a two-part reflector disposed in the rear thereof, one part of which is substantially coextensive in area with the central colored section and aligned therewith, the reflecting surfaces being disposed in such relation to each other that rays received through one of the sections of the lens are reflected through the other section of the lens in parallelism with the incoming rays.
- 15 2. A reflecting signal comprising a truncated conical reflector and a concentrically placed conical reflector, the two having their apexes in reversed position, and a glass plate covering the base of the larger reflector and having a central area of a warning color.
- 20 3. A reflecting signal comprising a truncated conical reflector and a concentrically placed conical reflector, the two having their apexes in reversed position, and a glass plate covering the base of the larger reflector and
- 25 having a central area of a warning color, and of a size corresponding with that of the base of the smaller reflector.
4. A reflecting signal comprising a truncated conical reflector and a concentrically placed conical reflector, the two having their apexes in reversed position, and a glass plate covering the base of the larger reflector and having a central area of a warning color, placed concentric with the axis of the reflector cones.
- 30 5. A reflecting signal comprising a truncated conical reflector and a conical reflector placed within the other with its base substantially coinciding with the small diameter of the other reflector and with its apex extending in a reverse direction, and a plate extending across the base of the outer reflector and having a central colored area of the same diameter as that of the base of the inner reflector and transparent without this area.
- 35 40 45

In testimony whereof I affix my signature.

WILLIAM LARKIN.
